Des. 813

Nicholas Müller, of New York A. Y.
Letters Patent No. 813, dated July 1st 1856

The schedule referred to in these Letters Patent and making part of the same:

To all whom it may concern:

Be it known that I, Nicholas Müller of the City, County and State of New York, have invented a new and original Design for Clock base fronts; and I do hereby declare that the following is a full, clear and exact description of the same referenced

being had to the accompanying drawings forming part of this specification, in which

Fig. 1. is a front view of a clock case front, showing my improved design.

Fig. 2. is a side view of the same.

Fig. 3. is a sectional profile through the line x, x, in Fig. 1. -

Similar letters of reference indicate corresponding parts in the several figures. -

The general character of this design is an eagle guarding war trophies. -

The clock case front A, is made with the usual opening B, which exposes the dial of the clock and the small opening C, through which the pendulum is exposed and regulated. -

On the base D, are arranged as shown various devices or implements, designed to represent trophies of war, of the character shown in the drawing and designated by the letters a, b, c, d, e; around, over and between which are arranged leaves of foliage, as shown and designated by the letters g, g; and placed upon the base D, is the figure of an eagle E, which is arranged under the dial and just a little forward of the trophies, with its body in the position shown and the claws of one of its feet resting upon some of the trophies and its wings spread so as to overhang and guard the nest, and with its head turned and thrown forward as though ready to pounce upon any intruder, as shown in Figs. 1 and 2. -

The eagle, trophies and foliage are formed in relief on the case front as shown in Figs. 2, and 3. -

3

Des.

843

What I claim as my invention and
desire to secure by Letters Patent, is

The war trophies, a, b, c, d, e, foliage g, g
and eagle H, when arranged and combined as shown,
to form an ornamental design for a clock case front. -
